UNITED STATES PATENT OFFICE.

ARTHUR EDWARD COOK CHAMBERLAIN, OF LONDON, ENGLAND, ASSIGNOR TO WILLIAM JOHN DENKER, OF LONDON, ENGLAND.

DETACHABLE HEELPIECE FOR FOOTWEAR.

Application filed August 28, 1926, Serial No. 132,295, and in Great Britain July 26, 1926.

This invention relates to an improved method of affixing rubber heels or other additional wearing surface elements suitable for affixing on the base of a heel of a shoe, in which the additional wearing member is replaceable when it becomes worn by a like member. More particularly does the present invention relate to detachable heel pieces of the type in which the detachable heel member has a hard portion on its upper or inner face which is provided with an aperture or recess to receive a resiliently supported projection carried by a co-operating member secured to the shoe heel, the method of attaching the heel member to the said co-operating member being by sliding one within the other by means of a co-operating projection and channel, until the resiliently supported projection engages in the said aperture or recess.

According to the present invention a detachable heel member of the above type comprises a plate adapted to be secured to the base of a shoe heel and carrying a leaf spring or resilient finger upon which is provided a projection adapted to engage in an aperture in a part of the detachable heel member.

In the preferred embodiment of my invention I provide a metal or other suitable hard plate having a periphery shaped to correspond with the outline of the heel to which it is to be attached, a further plate being secured upon the aforementioned plate and carrying on its inner face a leaf spring or resilient finger which is accommodated in a recessed or cut-away portion of the first mentioned plate, a channel or cut-away portion in the second mentioned plate adapted to receive a projection carried by the replaceable heel member, the said projection having an aperture adapted to receive a projection carried by the said leaf spring or resilient finger, the said replaceable heel member having an aperture in its wearing surface registering with the aperture in its said projection whereby a suitable tool may be introduced to depress the said projection to enable the wearing surface member to be slid out of place and if desired a new one substituted.

In order that my invention may be clearly understood and readily carried into effect, I have appended hereto a sheet of drawings

illustrating the preferred embodiment of same, and wherein:—

Fig. 1 is a plan view of the outer face of the plate carrying the leaf spring or spring finger and having the recess or channel to receive the projection carried by the replaceable member.

Fig. 2 is a plan view of the inner plate secured against the base of the heel and interposed between such base and the plate shown in Fig. 1.

Fig. 3 is a section to a larger scale on the line A—B of Fig. 1.

Fig. 4 is a section on the line C—D of Fig. 1, and

Fig. 5 is a plan view of the inner or upper face of the replaceable wearing surface member.

Referring to the drawings the heel of a shoe is indicated by the reference numeral 1 (see Figs. 3 and 4). The detachable wearing surface member 2 is preferably shaped to correspond in outline with the outline of the shoe heel and may be composed of rubber, leather or other suitable material. The member 2 has attached to it by splayed rivets 3 or other suitable means a projection 4 which is preferably of metal, but may be composed of other hard substance.

The projection 4 is disposed upon the inner or upper face of the wearing surface member 2 and it is of shallow dovetail cross section (see Fig. 3) whereby it may be slid into a correspondingly shaped opening 5 in a plate 6 which is secured to the shoe heel 1 by screws or other suitable elements 7. The inner end of the projection 4 is preferably radiused as indicated at 4^a, the opening 5 also being correspondingly radiused as shown at 5^a.

The dovetail section of the opening 5 and the projection 4 prevent the heel member 2 from dropping from the plate 5, and to prevent the projection 4 from sliding endwise out of the plate 5, a resiliently supported projection 8 is provided adapted to engage in a central opening 9 passing completely through the member 2 and the projection 4. The projection 8 is rounded to enable the projection 4 to be slid over it when affixing the member 2. To facilitate the initial part of the operation of sliding the projection 4 into the opening 5, the leading edge of the

projection 4 is formed with a rounded recessed portion 10.

The locking projection 8 is carried by the free end of a resilient strip 11 secured by a rivet 12 or other suitable means to the plate 6. The spring 11 is accommodated in a channel 13, which is obtained by forming a slot in a plate 14 interposed between the plate 6 and the heel 1 of the shoe.

10 When it is desired to remove a worn heel member 2, it is only necessary to insert a tool in the opening 9 to depress the projection 8 and to press the member 2 endwise to slide the projection 4 out of the opening 5.

15 I claim:—

A detachable heel piece for footwear comprising in combination a base plate for fixture to a shoe heel, having a dovetailed opening forwardly extending from the curved back of the heel, a downwardly-urged spring

tongue permanently fixed to the upper face of said base plate, extending in a rearward direction to beyond the inner extremity of the dovetailed opening and terminating at its free end at approximately the centre of 25 the heel, a thin intermediate plate for interposition between the base plate and the shoe heel with a slot extending completely through it shaped to conform to the spring tongue and adapted to accommodate said 30 tongue, a downward locking projection on the free end of the tongue, and a detachable wearing member having a dovetail projection extending forwardly from its curved rear edge and a hole extending through the 35 complete thickness of both the wearing member and dovetail projection for receiving the locking projection of the spring tongue, and allowing insertions of an unlocking tool.

ARTHUR EDWARD COOK CHAMBERLAIN.
